WRINGER RELEASE AND RESET
MECHANISM

Nicholas L. Etten, Waterloo, Iowa

Application November 27, 1939, Serial No. 306,306

1 Claim. (Cl. 68—262)

This invention relates to clothes wringers of the type used on domestic washing machines and has particular reference to the type of wringer in which the upper roll is carried on a top frame hinged laterally to the lower frame.

This type of wringer has a distinct advantage over the free top frame type because the frames are held together in positive relationship by the hinges although permitting wide separation of the rolls. Heretofore hinged top frame wringers have had serious faults, chiefly because the safety release usually functioned from the side opposite the hinges and usually releasing only in one direction, thus making the release different for the operator, depending on which side of the wringer she was standing.

It is the particular object of this invention to provide a laterally hinged top frame wringer structure in which the safety release bar is located centrally of the wringer and operates laterally in either direction from both sides.

Other objects and benefits will be disclosed in the following descriptions and drawings in which:

Fig. 1 is a cross-sectional side elevation view showing the interior parts of my wringer;

Fig. 2 is an enlarged end elevation view of my wringer as it would appear on the section lines 2—2 of Fig. 1 and with the wringer rolls locked in cooperating pressure relationship; and

Fig. 3 is an end elevation view similar to Fig. 2 except that the safety bar has been tripped and the rolls have been released from spring pressure.

Now referring to the drawings, I designate the lower frame of the wringer by the numeral 10, this lower frame having a top frame 11 hinged to it by dual hinges 12 and 13, one hinge, number 13, not showing because it is in alignment with the hinge 12 on the other side of the wringer, as will be well understood. Attached to the frame 10 of the wringer are conventional drain boards 14 and 15. This drain board structure is not pertinent to the present invention and will not be described in further detail, it being assumed that the wringer is equipped with conventional drain boards.

Mounted in the lower frame 10 is a lower wringer roll 16. It will be noted that this roll is not in this structure the drive roll and that it is resiliently supported practically independent of the driving mechanism. The trunnions of the roll 16 seat in conventional bearings 18 which are supported on a cross U-bar 19 resiliently supported by springs 21 and bolts 22 on shelf brackets 20, as clearly shown in Figs. 2 and 3. It will be

appreciated that the nuts of the bolts 22 are held in the channel 19 and pressure adjustment is conveniently provided by merely turning the heads of the bolts 22 when the top frame 11 is hinged backward to give easy access to the bolts.

The upper roll 17 is mounted on its inner end by conventional bearing 23 and the roll is supported in the upper frame 11 by the retainer clips 24 and the bolts 25. The outer trunnion of the roll 17 is supported in the bearing having a somewhat different structure but which is similar to the bearing support on the inner end in that a metallic bearing 23' with a similar support clip 24' supports the outer trunnion of the roll on a cross rib structure 34. This structure is made necessary in order to support the cam shaft 31, as will later be described.

A spur gear 26 is mounted on the inner end of the roll shaft 17. This spur gear is driven by a mating gear 27 driven by the horizontal shaft 28 through the conventional wringer gear head 29 controlled by the handle 30. The structure and operation of the wringer gear head are well understood and the same, not being pertinent to the present invention, will not be described in further detail.

It will be appreciated that the drive spur gear 27 is always held in the same relationship in the lower frame 10. The spur gear 26, mounted on the upper roll 17, is held in fixed relationship to the upper frame 11 as has been heretofore described. Now the upper frame 11, being hinged to the lower frame 10, is held in positive relationship to the lower frame 10 when they are locked together, as is clearly shown in Fig. 2. It will, therefore, be appreciated that by this structure I have provided effective means to drive the upper roll of the wringer while at the same time providing an effective roll stop when the upper frame is hinged backward, as clearly shown in Fig. 3. I arrange to prevent the upper frame 11 from being thrown too far backward by means of a stop ledge 12' on the hinge 12, as is clearly shown in Figs. 2 and 3. It will be appreciated that this stop ledge 12' will permit the rolls to be widely separated beyond any possible danger to the operator although the upper frame is held onto the lower frame by the hinge structure as described.

Now referring to Fig. 1, I show a locking cam shaft 31 mounted in cross ribs 34 in the upper frame 11. The outer end of the shaft 31 is merely passed through an opening or bore in the cross ribs 34, while the inner end of the shaft is

supported in a slot by means of the clip 36 and the bolts 37, as clearly shown in Figs. 2 and 3.

Now referring to Figs. 2 and 3, attention is directed to the formation of the cams 32 in the locking cam shaft 31. Dual cam surfaces are provided by milling cross slots which provide a rather sharp pointed cam design to lock the top frame on the short end, as clearly shown in Fig. 2. It will be appreciated that when the release handle 33, which is attached to the shaft 31 through slots 35 in the top frame 11,—is released by pushing laterally toward the hinges as shown in Fig. 3, the upper frame is released by rotative action of the shaft 31, as clearly shown in Fig. 3, it being appreciated that the springs 21 are urging the upper frame upward as will be readily appreciated by consideration of the positions of the cross bar 19 in Fig. 2 and Fig. 3. It will further be appreciated that when the release lever 33 is pushed or pulled laterally away from the hinges 12 and 13, that the other surface of the cam will permit the top frame to hinge upward in a similar manner. From the above description it will be understood that I have provided a release operable in either direction from both sides of the wringer.

The locking mechanism co-acting with the cams 32 consists of hinged lock bars 39 pivotally attached to the lower frame by the shoulder screws 38. The lock bars 39 have hooked cam surfaces 40 which co-act with the cams 32, as will be readily understood. Resiliently hinged to the bars 39 are guide bars 41 by means of the

shoulder screws 42 and the torsion spring 43 attached to the bars 39 by the screws 44.

The purpose of this structure will be readily appreciated by visualizing the co-action of the cam surfaces 40, the cams 32, and the guide bars 41 as the upper frame is tilted backward. It will be appreciated that the resilient mounting of the guide bars 41 continuously holds the locking parts in co-acting relationship so that when the upper frame is hinged downward on the lower frame, the various parts are in proper relationship to lock the frames together in co-acting roll pressure position. This condition is well illustrated in Fig. 3, and it is believed that with the above explanation, the function of the parts will be well understood.

Having thus described the invention, I claim:

In a clothes wringer, a lower frame, a lower roll, spring means urging said roll upward in the frame, a top frame hinged to the lower frame, a top roll including a through shaft journaled in said top frame, and pressure applying and release mechanism for urging the frames together in pressure sustaining position or for releasing said frames, said mechanism including a manually operable double release cam bar, said cam bar being journaled centrally in the upper frame and operable in either transverse direction, hook bars pivotally mounted in the lower frame, and resilient retainer mechanism on said hook bars to facilitate coaction between the hook and cam bars.

NICHOLAS L. ETEN.
